REFRIGERATING CONSTRUCTION

Frederick H. Hibberd, Bayside, N. Y., assignor to
Ingersoll-Rand Company, Jersey City, N. J., a
corporation of New Jersey

Application March 23, 1934, Serial No. 716,947

9 Claims. (Cl. 62—152)

This invention relates to a refrigerating construction, and particularly to a device and method for controlling a refrigerating system in which a liquid refrigerating agent or medium is employed to bring about the required cooling effect.

The invention is adapted for use with a multiple unit type of refrigerating apparatus in which refrigeration by evaporation is accomplished in one or more units according to the load requirements. An object of the invention is to provide means whereby the refrigeration output of the system may be controlled by shutting down or starting up one or more units without excessive manipulation of valves.

15 For refrigerating systems employing a non-volatile substance, such as water, as the refrigerant or cooling medium, an evaporator in the form of a container for water to be chilled is employed. The pressure in this evaporator is kept at a relatively low point, so that when water is admitted thereto at a given temperature, some of the water is vaporized at once. In this way a body or mass of water in the evaporator can be cooled to the necessary extent and utilized for 20 the purpose in view. The water vapor obtained from vaporization of part of the water must be removed from the evaporator, and this may be accomplished by a steam ejector which exhausts to a condenser wherein the discharge of the 25 ejector is liquefied.

With an evaporator having a single chamber and steam ejector such a system will serve quite well at approximately fixed or predetermined loads, but it is quite unsuitable for practical operation when the load varies. Hence if such a system is built for a rated load it cannot be operated advantageously to give a reduced output, and if it is built for a small load the output cannot greatly be increased. This is due to the fact 30 that the capacity of the steam ejector or steam jet booster, that is, the pounds of water vapor evacuated thereby at fixed suction pressure determined by the pressure in the evaporator itself, is substantially constant, regardless of the 35 amount of steam being used. Further, it is a characteristic of the steam jet booster that its steam flow must be maintained at the rated value 40 so long as the suction pressure (or the chilled water temperature) in the evaporator and discharge or condenser pressure remains constant. Hence this type of steam jet must therefore be turned on completely, using its full rated steam 45 consumption, or completely off and rendered inoperative, so long as the operating pressures 50 remain at their normal values. But with a re-

frigerating system of this character which comprises several evaporator chambers and steam ejectors, connected in multiple and adapted to work with either all of its evaporator chambers and ejectors, or less than all of said chambers and ejectors in operation, the load can be varied within quite widely separated limits, steam can be saved under conditions of reduced load and the consumption or expenditure of power is thus adjusted to the quantity of refrigerating effect 10 that is actually obtained.

This invention is especially designed to be employed with refrigerating systems including a plurality of chambers for evaporating and cooling water and a steam ejector for each chamber, 15 with proper connections for the operation of one or more of said chambers; a further object thereof is to provide a refrigerating system having multiple evaporator chambers with supply means disposed in permanent free communication with 20 said chambers and so arranged that water to be chilled is admitted to only the chambers of the evaporator which really are in operation and use, the inflow of water to any chamber which is cut out being automatically interrupted so that 25 said chamber remains virtually empty until the operation thereof is resumed.

Another object of the invention is to provide a refrigerating system, having a water evaporator comprising a chamber or chambers of such interior design that the admission of water thereto is at once prevented whenever the evacuation of water vapor therefrom is stopped. This mode of action is obtained solely as the result of working conditions in any chamber which is thus put out 30 of operation, and no valves or the like elements 35 to be manipulated in the water supply connections are needed.

An additional object of the invention is to provide a refrigerating construction embracing an evaporator with one or more chambers in which part of a liquid refrigerant is vaporized to cool the main body of said refrigerant, and with another chamber in which no substantial refrigerating effect is produced and which has for its 40 function the automatic maintenance of the proper level of the chilled water in the other chambers.

The objects and advantages of the invention are completely set out in the following description, but the disclosure is explanatory only, and many changes that are embraced within the principle of the invention can be made, as indicated by the broad terms in which the appended 50 claims are expressed.

In the drawing, Figure 1 shows an outline of a refrigerating construction according to the invention, partly in section,

Figure 2 is a sectional view taken on the line 5 2-2 of Figure 1, and

Figure 3 is a view similar to Figure 2 showing an evaporator chamber that is not operating.

In the drawing the same numerals identify the same part throughout.

10 I show at 1 a water evaporator having a supply pipe 2 and an exhaust or delivery pipe 3, the water being admitted to the evaporator 1, and after being cooled therein, being withdrawn through the conduit or header 3 and carried off 15 thereby. The evaporator 1 contains several compartments or chambers 4, 5, 6, and 7, formed by the ends of the evaporator and transverse partitions 8, a portion of the incoming water being vaporized in one or more of these chambers. The 20 water vapor is removed by means of suitable evacuator members, such as steam ejectors or steam jet boosters 20. The steam ejectors remove the water vapor from the chambers and in so doing maintain the high vacuum necessary for 25 vaporization and chilling of the incoming water to the temperature desired. These boosters communicate with the top of the chambers and discharge into a steam exhaust pipe 9. This exhaust pipe communicates with a conventional 30 type of condenser wherein the evacuated vapors and operating steam are condensed at a somewhat higher pressure than that in any of the chambers where water vapor is thus created. The steam ejectors for all the chambers of the evaporator 1 are supplied from a common steam line 10.

The terminal portion of the water supply pipe 2 is inside the evaporator 1, and has sections 11 in the chambers 4, 5, 6, and 7. It delivers to the chamber 4 through a comparatively small upright branch pipe or well 12, and the other chambers through lateral branches indicated in Figure 2 at 13. The common delivery pipe 3 communicates with the bottom of all the chambers through branches or riser pipes 14 by way of 45 outlet openings 15. The communication between the conduit 3 and any of the chambers of the evaporator is always free because no valves are employed in either the delivery pipe 3 or any of the branches 14. So long as the various chambers 50 are in operation and water is vaporized therein and water vapor removed therefrom, the water in the various chambers will be cooled to the required extent. If, however, one of the compartments is put out of operation by closing the booster steam valve, the level of the cooled 55 water therein will automatically sink, for the chilled contents of this particular chamber will be forced out because the pressure in that chamber rises to condenser pressure. But enough of the water will be trapped in the riser connected 60 to that chamber to seal it and keep it from communicating with the other chambers. As this method is fully set forth in my co-pending application, Serial No. 716,945, for patent on Refrigerating apparatus, filed of even date herewith, that part of the apparatus herein described which gives this function is therefore not recited in the claims hereunto appended.

When one of the boosters is turned off for 70 purposes of saving steam as described above, and condenser pressure is exerted in the corresponding evaporator chamber, the water to be chilled must be prevented from entering this inactive chamber. This is necessary because the inactive chamber is now in free communication with the

condenser and if relatively cold water enters that chamber it will become heated by the condensing therein of the discharge steam from the boosters active in evacuating other chambers. Part or all of the desired refrigerating effect will therefore be 5 lost. Therefore each of the chambers 5, 6, and 7 is provided with a weir 16 adjacent one side of the chamber which extends longitudinally between the partitions 8 and one end of the evaporator 1. Each weir begins at the bottom and 10 extends toward the top. Each of the weirs together with the adjacent portions of the wall of the evaporator 1 provides a space or well 18 into which the water is admitted through the adjacent branch 13 delivering to the well near the 15 bottom, as shown in Figure 2, and a certain portion thereof will be vaporized at once as it flows over the weir. If desired each weir may have openings 17 near the top through which the water therein may be delivered. Such a construction has the advantage that the proper distribution of water to the various chambers is more easily obtained and controlled, as it prevents slight variations of vacuum from interfering with the flow of the refrigerant.

To carry away the water vapor, each of the chambers 4, 5, 6, and 7 has an outlet 19 in the top leading to steam ejectors or steam jet boosters 20. These are in the form of L-shaped tubular members which communicate at one end with the 30 outlets 19 and are connected to their opposite ends to the conduit 9 into which they discharge. Each ejector has a steam nozzle 21 connected by pipe 22 to the steam line 10 and each branch pipe carries an admission and shut-off valve 23. The 35 ejectors for the chambers 4, 5, 6, and 7 all discharge into the conduit 9 leading to the condenser (not shown), but the ejector for the chamber 4 is of much smaller size and capacity than the others and serves a special purpose described 40 below. The chamber 4 is not provided with a weir but the inlet pipe 12 extends from the bottom as high as the weirs 16 in the other chambers. All of the weirs are, of course, of the same 45 height.

In operation, water to be cooled may enter all the chambers through the branches 13 and the inlet pipe 12, and as part of it is vaporized, the water vapor is removed by the steam ejectors through the pipe 9 and compressed to the pressure in the condenser. The water, which is chilled by the vaporization of part thereof, passes out through the risers 14 and the delivery conduit 3 as above set forth. So long as the steam jets are supplied from the line 10 the vacuum in 55 the chambers remains low, but if any one of the steam jets is shut off the absolute pressure in the chamber to which that jet is connected, will increase and become equal to the pressure of the condenser. This pressure will depress the level 60 of the inflowing water in the well 18 below the tops of the weir or openings 17 in that chamber, so that no more water can enter the chamber that is not being evacuated. This condition is shown in Figure 3, which illustrates the manner 65 in which the continued admission of water to the well in that chamber is stopped as set forth above.

The remaining chambers will continue in operation and discharge the chilled refrigerant through 70 the common delivery conduit 3. The condenser pressure in the chamber which is cut out will compel the conduit 3 to drain that chamber down to a point which will be generally in the riser 14 below the outlet opening 15 thereof. The 75

risers, however, will be high enough so that some of the water will be trapped in the riser connected to the chamber which is not working, and will seal the latter from below, and the greater pressure in the non-operating chamber will be prevented from taking effect in any of the other operating chambers. This condition is shown in the chamber 1 on Figure 1.

In practice the evaporator will be operated by including all the chambers or by cutting out one or more of the chambers 5, 6, and 7. Chamber 4 must always be in operation because it contains a float which actuates a valve 26 in the water supply line 2, within the chamber 4. This valve is a rotary valve having an arm 27 and a rod 28 which is connected to a bell crank lever which supports the regulating element or float 29. This float so actuates the valve 26 that the water is maintained at a constant level in the chambers of the evaporator independent of the rate of outflow. If this water level drops the valve is opened further, and if the water level tends to rise it is moved towards closed position. The steam jet for the chamber 4 is somewhat smaller than the other steam jets and is so proportioned that it will maintain the same vacuum in this chamber as in the other chambers which are working.

This is insured by admitting only a small amount of water through the small conduit 12, thereby establishing the temperature and pressure in chamber 4 as substantially the same as that in the other active chambers.

It should be noted that the pipe 12 and the booster for the chamber 4 are of such relatively small capacity that no substantial refrigerating effect is produced. The sole function of this booster and its chamber 4 is to maintain the proper water level in the active chambers, irrespective of which ones are in use without necessitating the manipulation of any valves for putting any of the chambers into or out of service.

With all the chambers in communication with one another through the risers 14, the cooled water therein tends to seek the same level in the chambers that are working, because each working chamber is subjected to the pressure head of the cooled water in the other working chambers. This level will be constant because the vacuum maintained by the steam jets in all the working chambers is the same. When any chamber is cut out of operation, the admission of further water thereto from the pipe 2 is prevented because the higher condenser pressure in that chamber forces the level of the inflowing water in the well a material distance down below the top, while the water already chilled in that particular chamber is forced out and that chamber is emptied except for a portion which remains in the riser pipe, at the level indicated in the riser 14 of the chamber 1, for example, in Figure 1, to seal this chamber. The pump 29' in the line of the conduit 3 insures the transmission of the cooled water to the place of use.

The end of the pipe 2 outside of the evaporator is shown as having a flange 30 to facilitate securing it to the outside of the chamber 4, so as to deliver through an inlet 31 to the portion of this supply pipe which is inside of the evaporator 1. The valve 26 is in the line of this pipe inside the evaporator, as are also the lever carrying the float, the connecting rod 28 and the arm 27. Hence, no stuffing box or packing need be provided for this rod, such as would be necessary if

the valve 26 were outside of the evaporator. The casing for this valve has flanges to enable it to be joined on one side to a flange of a section of the pipe 2 inside the evaporator leading to the inlet 31, where this section has a similar terminal flange to enable it to be secured to the wall of the evaporator around the inlet 31, the same as the outside pipe 2, and on the other side to another section leading to the first of the remaining chambers. The inside partitions 8 have openings 32 so that the sections 11 can be secured by similar end flanges to the partitions 8 around the openings 32, and the lateral branches 13 lead to openings 33 in the weirs 16 adjacent the bottoms thereof. Pipe 12 is likewise secured to the pipe 2 by a flange at its lower end, and the branches 13 are similarly united to the weirs 16 around the openings 33, the numeral 30 indicating all of the flanges above mentioned.

It will be seen that, as illustrated in Figure 2, the level of the inflowing water in any chamber which is operating is at a predetermined discharge point in the well thereof, and is higher than the level of the chilled water in the bottom of any working chamber, where it collects before passing out through the risers 14. Vaporization of part of the water takes place as the incoming water flows downward from the upper portions of the wells 18 and the pipe 12, which is also, in effect, a well. As long as the water vapor is sufficiently evacuated from any chamber by the members 20, the level of the incoming water remains high enough to be discharged from the well, and when the vacuum is lessened upon the stoppage of any one of the steam jet boosters, the increase of absolute pressure to condenser pressure within the chamber which is put out of operation empties that chamber because the pressure forces down the level of the incoming water so that no more vaporization is accomplished and at the same time it depresses the level of the chilled water therein to the point indicated in connection with the riser 14 connected to the chamber 1.

The system may be operated so that, when a chamber is cut off the total quantity of refrigerant is correspondingly reduced. Then the same quantity of refrigerant as before flows through each of the remaining chambers and at the same rate. Or the operation may be such that the quantity of liquid remains as before, when one or more chambers are stopped and thus the body of refrigerant passes at an increased rate through the remaining chambers.

I claim:

1. A refrigerating construction comprising an evaporator containing a plurality of chambers, means for supplying a liquid refrigerant part of which is to be vaporized in said chambers, means for evacuating vaporized refrigerant from said chambers, means for delivering the remainder of the liquid refrigerant from said chambers, a valve in the supply means on the inside of said evaporator, and a regulating element in one of said chambers connected to said valve arranged to maintain the liquid in said chambers at a substantially constant level.

2. The method of producing and controlling refrigeration which consists in dividing a liquid refrigerant into separate quantities, supplying each quantity independently from a common source, causing the discharge of each quantity from a predetermined level to a lower level and simultaneously vaporizing a portion thereof, and stopping the discharge and vaporization of any one of said

- quantities by increasing the pressure upon it and thereby depressing its surface below the discharge level, without interrupting vaporization of portions of the remainder of said refrigerant.
5. 3. The method of producing and controlling refrigeration which consists in treating a liquid refrigerant in separate quantities by supplying each quantity independently, maintaining a vacuum above each quantity, keeping the surface of each 10 quantity at a predetermined level, causing the discharge of each quantity from said level under the influence of said vacuum and simultaneously vaporizing a portion of said quantity, and stopping the discharge and vaporization of any one of said 15 quantities by decreasing said vacuum and thereby depressing the surface of said quantity below the discharge level without stopping vaporization of portions of the remainder of said refrigerant.
20. 4. The method of producing and controlling refrigeration which consists in passing a liquid refrigerant through separate spaces, treating the refrigerant by creating a vacuum in each of said spaces to vaporize a part of the refrigerant therein, removing and compressing the vapor so formed, and increasing the pressure in any one of said spaces to empty same and suspend the passage of refrigerant thereinto while continuing the passage of refrigerant into the other spaces.
25. 5. The method of producing and controlling refrigeration consisting in passing a liquid refrigerant through separate spaces, treating the refrigerant by creating a vacuum in each space and vaporizing a part of the refrigerant therein, removing and compressing the vapor so formed, and subjecting any of said spaces to the increased pressure of the removed vapor from other spaces to empty the space so subjected and stop the passage of refrigerant thereinto to suspend vaporization in the space while continuing the passage of refrigerant into and the vaporization 30 thereof in the remaining spaces.
35. 6. A refrigerating construction comprising an evaporator containing a plurality of chambers, means for delivering liquid refrigerant to each 40
- chamber, means for withdrawing said refrigerant, independent evacuating means to facilitate vaporization of part of the refrigerant in each chamber, and connections whereby the pressure in each chamber can be increased to empty same 5 and suspend the delivery of refrigerant thereto and the vaporization therein while the remaining chambers continue to be active.
7. Refrigerating apparatus comprising an evaporator having a plurality of chambers connected 10 in parallel, evacuating means for each chamber to reduce the pressure therein and to remove vapor therefrom, a well in each chamber having its upper opening above the bottom of the chamber, means common to all the chambers to introduce refrigerant to the well near its bottom, means to withdraw chilled refrigerant from the chambers, and means associated with the evacuating means to increase the pressure in a chamber and thereby prevent the admission of refrigerant thereto.
8. Refrigerating apparatus comprising an evaporator having a plurality of chambers, evacuating means for each chamber to reduce the pressure therein and to remove vapor therefrom, 25 means to withdraw chilled refrigerant from the chamber, means to start and stop the action of the evacuator to decrease or increase the pressure in the chamber, and means including a well in the chamber to admit refrigerating medium to 30 the chamber when the evacuator is operating and to prevent such admission when the evacuator is inoperative, without affecting the operation of any other chamber.
9. Refrigerating apparatus comprising an evaporator having a plurality of chambers, evacuating means for each chamber to reduce the pressure therein and to remove vapor therefrom, means to remove refrigerant from the chamber, and means including a well in each chamber to control the 35 admission of refrigerant to the chamber in accordance with the pressure maintained therein, without interference with the admission of refrigerant to any other chamber.

FREDERICK H. HIBBERD. 45
